[57] CLAIM

The ornamental design for a hair treatment solution collector and receptacle, as shown and described.

DESCRIPTION

FIG. 1 is a perspective view of a hair treatment solution collector and receptacle showing my new design;

FIG. 2 is a top plan thereof;

FIG. 3 is a right side elevation thereof, with the left side elevation being a mirror image thereof;

FIG. 4 is a bottom plan thereof;

FIG. 5 is a front elevation thereof; and

FIG. 6 is a rear elevation thereof.
